UNITED STATES PATENT OFFICE.

TOM MELLOR, OF BRANDON, MANITOBA, CANADA.

BLACKBOARD.

1,344,920.

Specification of Letters Patent. Patented June 29, 1920.

Application filed April 26, 1920. Serial No. 376,767.

To all whom it may concern:

Be it known that I, Tom MELLOR, of the city of Brandon, in the Province of Manitoba, Canada, have invented certain new and useful Improvements in Blackboards, of which the following is the specification.

The invention relates to improvements in blackboards, particularly as used in schools and other public places and the general object of the invention is to provide a blackboard arranged and constructed so that it will not reflect light directly into the eyes of the pupils or observers thereby allowing any material written on the blackboard to 10 be plainly visible to all observers.

A further object of the invention is to provide a pivotally suspended counterbalanced blackboard which can be readily adjusted by hand manipulation and which can 20 be easily set in any inclined position depending on the conditions existing.

A further object is to arrange the parts so that it can be readily installed on a wall.

With the above more important objects in view the invention consists essentially in a plurality of brackets permanently attached to the wall and forming pivot supports for the blackboard, counterbalancing means attached to the upper end of the 25 blackboard and means for detachably fastening a map or such like to the blackboard, the parts being arranged and constructed as hereinafter more particularly described and later pointed out in the appended 30 claims, reference being had to the accompanying drawings in which:—

Figure 1 is a front view of a blackboard constructed in accordance with my invention.

40 Fig. 2 is a plan view thereof.

Fig. 3 is an enlarged detailed vertical sectional view through the blackboard and looking directly at one form of bracket used.

Fig. 4 is a view similar to Fig. 3 and 45 looking directly at the other form of bracket used.

Fig. 5 is a plan view of one of the jam brackets.

Fig. 6 is a side view of the same.

50 Fig. 7 is a vertical sectional view at 7—7' Fig. 6.

Fig. 8 is a side view of one of the rocker brackets which I use.

Fig. 9 is a front view of the rocker bracket.

Fig. 10 is a sectional view at 10—10' Fig. 8.

Fig. 11 is an enlarged detailed vertical sectional view through the chalk rail.

In the drawings like characters of reference indicate corresponding parts in the several figures.

In connection with the following description, I wish it to be understood that the blackboard can be of any length, depending on the size of the room and the requirements and that it can be attached to the wall of the room or to any other solid support.

1 represents the wall of the room and 2 the blackboard which is adjustably suspended from the wall in a manner shortly described. The blackboard is formed from an open centered rectangular frame 3 in which I insert slate or such like sections 4 forming the writing surface of the board and these sections are reinforced at the back by applied battens or reinforcing strips 5 permanently secured at suitable spaced intervals to the frame. A chalk rail 6 is permanently secured to the lower part of the frame and is supplied with the customary lengthwise extending chalk groove 7.

The blackboard is pivotally suspended from the wall by two sets of specially constructed supporting brackets, there being four brackets of the one type used and five of the other in the present disclosure. The brackets 8 of the first type are shown best in Figs. 5, 6 and 7 and it will be observed that they present each a circular or disk like head 9 and a flanged base 10 and that the head is connected by an adjusting bolt 11 to a disk like head 12 formed as part of a hanger 13. The hanger is fitted with two 95 screw holes 14 and 15 and the disks have their adjoining faces frictionally engaged, being held in contact by the bolt which forms also a pivoted connection between the hanger and the bracket.

The second form of bracket 16 presents a cross groove 17 instead of a disk head and in the cross groove I form a rounded pocket 18 for the purpose shortly described. It is also provided with a flanged base 19 similar 105 to that 10.

20 is a hanger provided with a V-shaped head 21 which rests in the groove 17 and the head is fitted with a tongue like extension 22 which rides in the pocket. 23 is a base plate formed as part of the hanger and provided with side notches 24 for fastening purposes.

In referring to Fig. 2 it will be seen that I have used four of the brackets 9 with associated hangers and five of the brackets 16 with associated hangers to suspend the blackboard.

In actual practice the flanged bases of the brackets are permanently secured as by bolting or screwing to uprights 25 permanently fastened to the wall, while the base plates of the hangers are attached permanently to the battens 5, the bases 23 being screwed centrally to the rear faces of the battens while the hangers 13 are screwed through the openings 14 and 15 to the sides of the battens.

By observing Figs. 3 and 4 it will be seen that the blackboard is actually pivotally suspended from the wall by the brackets and hangers, the pivot points being located just slightly to the rear of the longitudinal axis of the blackboard. At suitable intervals I connect to the top edge of the blackboard frame a plurality of cables, ropes or such like flexible connections 26 which pass inwardly toward the wall and over pulleys 27 fastened to the wall. The inner ends of the cables are supplied with counterbalancing weights 28, which work up and down adjust the wall and can be incased if desired.

From the above arrangement it will be observed that the brackets and hangers 16 and 20 carry their proportion of the weight of the blackboard and while forming a pivot support and that the disk like heads of the brackets 8 and hangers 13, while also carrying their proportion of the weight of the blackboard and forming a pivot support, provide also of a friction adjustment as obviously one can by tightening up the bolts 11 increase or decrease the friction at the joints.

By properly adjusting the bolts one can set the blackboard to the preferred inclined position and obviously the counterbalancing weights relieve the engaged friction faces to a considerable extent.

The whole arrangement is such that one can very easily adjust the board, such being possible through the combined action of the friction faces and the counterbalancing weights.

In order to allow of the easy attachment of a map or such like to the front face of the board I have provided a pair of hooked extension arms 29 and 30 on the top side of the board which are designed to receive the customary hanging rings or hanging eyes of the map 32 and the lower binding strip 33 of the map is caught beneath the spring

clips 34 secured to the chalk rail and adapted to jam the strip in the chalk groove as best shown in Fig. 11.

What I claim as my invention is:—

1. The combination with the wall of a room and a blackboard, of a plurality of horizontally aligned hangers and brackets pivotally suspending the blackboard from the wall and with the pivot point positioned to the rear of the longitudinal axis of the blackboard and with certain of the brackets and hangers presenting engaging friction faces.

2. The combination with the wall of a room and a blackboard, of a plurality of horizontally aligned hangers and brackets pivotally suspending the blackboard from the wall and with the pivot point positioned to the rear of the longitudinal axis of the blackboard and with certain of the brackets and hangers presenting adjustable engaged friction faces.

3. The combination with the wall of a room and a blackboard, of a plurality of horizontally aligned hangers and brackets pivotally suspending the blackboard from the wall and with the pivot point positioned to the rear of the longitudinal axis of the blackboard and with certain of the brackets and hangers presenting engaging friction faces and counterbalancing means attached to the upper part of the blackboard.

4. The combination with the wall of a room and a blackboard, of a plurality of horizontally aligned hangers and brackets pivotally suspending the blackboard from the wall and with the pivot point positioned to the rear of the longitudinal axis of the blackboard and with certain of the brackets and hangers presenting engaging friction faces and counterbalanced weights attached to the upper side of the blackboard.

5. The combination with the wall of a room and a blackboard, of a plurality of horizontally aligned hangers and brackets pivotally suspending the blackboard from the wall and with the pivot point positioned to the rear of the longitudinal axis of the blackboard and with certain of the brackets and hangers presenting engaging friction faces, a plurality of flexible connections attached to the upper edge of the blackboard and passing rearwardly toward the wall and downwardly over pulleys secured to the wall and counterbalancing weights secured to the lower ends of the flexible connections.

6. The combination with the wall of a room and a substantially rectangular horizontally disposed blackboard, of a plurality of brackets and hangers pivotally suspending the blackboard from the wall with the hangers attached to the blackboard and with the brackets secured to the wall and having the pivot point of the blackboard located to the rear of the longitudinal axis thereof and

certain of the associated brackets and hangers presenting engaged friction faces and provided with adjusting bolts for increasing or decreasing the frictional contact and a plurality of counterbalancing weights attached to the upper edge of the blackboard.

7. The combination with a horizontally disposed pivoted blackboard and a grooved chalk rail located at the lower edge of the blackboard, of a pair of suspension arms

secured to the upper edge of the blackboard and a plurality of spring clips secured to and operating within the groove of the chalk rail.

Signed at Brandon, this 8th day of March 1920.

TOM MELLOR.

In the presence of—

C. BLAKE,

A. C. GARDINER.
